WEATHER SEAL

Stanley J. Czerwicznik, Milwaukee, Wis.

Application October 14, 1944, Serial No. 558,656

1 Claim. (Cl. 20—68)

1

The present invention relates in general to improvements in weather seals, and relates more specifically to improvements in the construction and operation of weather stripping for doors, windows or other similar closures.

The primary object of my invention is to provide a new and useful weather seal for doors, windows, or the like, which is simple in construction and highly effective in use.

Many different types of so-called weather stripping have heretofore been proposed and used commercially for diverse purposes and with varying degrees of success, and while it is a relatively simple matter to weather seal sliding windows or the like with the aid of interfitting and relatively slideable resilient metallic strips, it is far more difficult to effectively seal swinging doors and windows especially if any warping or other distortion is present in the bodies or frames thereof. Then too, the resilient metal used in many of the prior weather strips has recently been obtainable only in relatively small quantities and at high cost, while wood and other relatively resilient non-metallic materials are more readily available at considerably lower cost. While it has also been proposed to utilize wooden and other non-metallic weather stripping for swinging doors or the like, these prior sealing devices were either too complicated and expensive, or they could not be readily applied to existing doors, or they failed to effectively accomplish their intended purpose especially when the swinging doors or windows were warped or otherwise distorted.

It is therefore a more specific object of the present invention to provide an improved yieldable weather strip especially applicable to swinging door assemblies or other closures, and which will effectively seal the door opening even if the swinging door or other member is warped or otherwise distorted.

Another specific object of this invention is to provide an improved sealing strip for swinging doors or the like, which may be readily applied to the upright or horizontal jambs, or other parts of any existing standard swing door installation.

A further specific object of my invention is to provide a relatively simple, compact, and neat appearing flexible weather strip, which may be manufactured and sold at moderate cost.

Still another object of the invention is to provide a durable seal strip assemblage which may be furnished or cut into any desired lengths, and which functions to automatically conform with the contour of coacting closures throughout the length thereof.

2

These and other specific objects and advantages of the invention will be apparent from the following detailed description.

A clear conception of the features constituting my present improvement, and of the construction and operation of a weather strip embodying the invention, may be had by referring to the drawing accompanying and forming a part of this specification, wherein like reference characters designate the same or similar parts in the various views.

Fig. 1 is a fragmentary part-sectional outside view of a piece of the improved elongated weather stripping, showing the flexible plunger bar in its outermost position, and the section having been taken centrally of the molding strip and plunger bar;

Fig. 2 is a transverse section through the improved weather strip taken along the line 2—2 of Fig. 1, and showing the same applied to a door jamb and about to coact with a closing swing door;

Fig. 3 is a transverse section through the same weather strip taken along the same line 2—2, but showing the door closed and coacting with the flexible plunger bar;

Fig. 4 is another transverse section through the weather strip assemblage taken along the line 4—4 of Fig. 1, and showing the plunger bar in its outermost position and the assemblage attached to a door jamb; and

Fig. 5 is another section similar to that of Fig. 1 taken centrally and longitudinally through a fragment of the improved door sealing strip, but showing the plunger bar and one of the leaf springs coacting therewith, depressed as in Fig. 3.

While the invention has been shown and described herein as being especially adapted for embodiment in sealing strips applicable to standard door jambs in the form of stop strips, it is not my intention or desire to thereby unnecessarily restrict the scope or utility of the improvement.

Referring to the drawing, my improved weather strip as shown therein by way of illustration, comprises in general an elongated molding strip 8 having a rectilinear groove 9 therein and extending throughout its entire length; a flexible plunger bar 10 snugly but slidably confined within the groove 9 by means of a series of parallel nails 11 having heads 12 coacting with local recesses 13 formed in the bar 10; and a series of approximately semi-circular resilient elements or leaf springs 14 disposed within the groove 9 beneath the bar 10 and coacting at their opposite ends 55 with the groove bottom, and at their medial por-

tions with arcuate notches 15 formed in the inner edge of the bar 10.

The elongated molding strips 8 may be of any desired length, and may be formed of any suitable and durable material such as wood, plastic, or the like, and the grooves 9 should be accurately formed of uniform cross-sectional area throughout their lengths. Each of the molding strips should also be provided with a series of local holes 16 adapted for the reception of fastening elements such as screws 17 in order to permit ready attachment of the weather strip assemblies to the top and side jambs 18 of a swing door 19, as shown in Figs. 2, 3 and 4; and the holes 16 are preferably disposed equi-distant apart.

The elongated flexible plunger bars 10 which snugly but slidably engage the grooves 9 of the molding strips 8, may also be formed of suitable relatively bendable material such as hard wood, plastic or the like, and should be of substantially the same lengths as the strips 8 with which they cooperate. As shown, the transverse cross-sections of the bars 10 are rectangular, and the flexibility of the plunger bars is enhanced by the successive notches 15 which are formed in the bars 10 at relatively close intervals spaced equi-distance apart. The nail receiving recesses 13 are similarly spaced along the length of each plunger bar 10, and are located between the successive notches 15; and these recesses 13 are of definite depth and are provided with parallel pre-formed concentric holes 20 extending from the recess bottoms through the inner portions of the bars 10 and slidably engaging the parallel guide nails 11.

The guiding and limit stop elements or nails 11 may be standard finish nails driven firmly into the body of the molding strip 8 so that the heads 12 of all of the nails will be equi-distant from the bottom of the groove 9, whereby the bars 10 may move or slide into the grooves 9, but have their outward motion positively stopped or arrested by the nail heads 12 contacting the bottoms of the recesses 13. The fastening screws 17 may also be of any suitable standard type, preferably located between successive nails 11; and the resilient leaf springs 14 are preferably formed of spring metal or other suitable material, and tend to force the bar 10 outwardly toward the nail heads 12 at all times. As previously indicated, there is a series or succession of these springs 14 provided in each weather strip assembly, and the curved leaf springs 14 are normally retained in proper position and are prevented from shifting by the successive notches 15 with which they coat.

The improved elongated weather strip assemblies may be manufactured and sold in various lengths, and may be cut to suit particular requirements, and they may also be produced in various commercial sizes. When the molding strip 8, bar 10, and springs 14 have been properly constructed, it is a simple matter to complete a weather strip assembly by merely inserting the nails 11 within the holes 20, and by subsequently driving these nails into the body of the strip 8 after the successive springs 14 have been properly positioned within their confining notches 15. In driving the nails 11, care should be exercised in finally positioning the nail heads 12 equi-distant from the bottom of the groove 9, and the outer edge of the bar 10 may finally be provided with a strip of felt, if so desired, in order to conceal the

nail holes 13 and to deaden sound. After the weather strips have been cut to proper length, they may be fastened to the top and side jambs 18 for proper cooperation with a swing door 19.

During normal use of the improved weather strips when thus applied to a door assembly, when the door 19 is open, the retractable bars 10 of the weather strips will be in outermost position stopped by the nail heads 12, as shown in Figs. 1, 2 and 4, by virtue of the action of the leaf springs 14 coacting with the notches 15 and with the bottoms of the recesses 9. However, when the door 19 is swung into closed position as shown in Figs. 3 and 5, the springs 14 will be distorted and the bars 10 will be forced into the recesses 9 thereby causing the nail heads 12 to move away from the bottoms of the recesses 13. If the portions of the door 19 which engage the bars 10 are perfectly straight, all of the springs 14 will be distorted like amounts, and all portions of the bars 10 will move into the adjacent recesses 9 equal amounts. However, if the door surfaces are warped, some of the springs 14 will be distorted lesser amounts than others, and the springs will then flex or bend the bars 10 so as to insure intimate contact between the outer bar edges and the adjacent distorted door surfaces, thus insuring effective sealing even under such abnormal conditions. When the door 19 is again swung away from the bars 10, the springs 14 will become quickly effective to restore the weather strip assemblies to the condition shown in Figs. 1, 2 and 4, preparatory to subsequent sealing when the door is again closed.

From the foregoing detailed description it will be apparent that my present invention provides an improved weather strip assemblage which besides being extremely simple, durable and compact in construction, is also highly efficient in use. The improved weather strips may be furnished in various lengths and sizes in order to meet different conditions of use, and may be assembled at moderate cost from relatively simple and standard parts. The leaf springs 14 and the flexible bars 10 will insure tight sealing of the joints even if the door or other closure is warped, or distorted, and while the weather strip has been shown herein as being advantageously applicable to the top and side jambs of a door, the improved assemblages may also be applied to the doors themselves and to other types of closures. The weather strips embodying the present invention may obviously be manufactured and sold at moderate cost and are readily applicable by a novice so as to effectively perform their intended functions.

It should be understood that it is not desired to limit this invention to the exact details of construction or to the precise mode of use, herein shown and described, for various modifications within the scope of the appended claim may occur to persons skilled in the art.

I claim:

A weather seal comprising, an elongated rigid molding strip having a rectilinear groove extending throughout its length, a similarly elongated flexible bar snugly but slidably confined within said groove and having a series of arcuate notches facing the groove bottom and locally reducing the cross-sectional area of the bar to enhance the flexibility thereof, and a series of approximately semi-circular leaf springs concealed within said groove and each having its medial portion loosely disposed within one of said notches and its op-

posite ends freely slidably cooperable with said groove bottom.

STANLEY J. CZERWICZNIK.
